UNITED STATES PATENT OFFICE.

JAMES R. CRAVATH, OF CHICAGO, ILLINOIS, ASSIGNOR TO NATIONAL X-RAY REFLECTOR COMPANY, OF CHICAGO, ILLINOIS, A CORPORATION OF ILLINOIS.

DESIGN FOR A REFLECTOR.

44,086.

Specification for Design.

Patented May 27, 1913.

Application filed April 14, 1913. Serial No. 761,068. Term of patent 7 years.

To all whom it may concern:

Be it known that I, JAMES R. CRAVATH, a citizen of the United States, residing at Chicago, in the county of Cook and State of Illinois, have invented a new, original, and ornamental Design for Reflectors, of which the following is a specification, reference being had to the accompanying drawing, forming part thereof.

Figure 1 is a side elevation, showing my

new design; Fig. 2 is an elevation at right angles to Fig. 1.

I claim:

The ornamental design for a reflector, as shown.

JAMES R. CRAVATH.
